ATTORNEY

UNITED STATES PATENT OFFICE.

FRANK M. SALMON, OF GALESBURG, ILLINOIS.

REFRIGERATOR.

1,283,926.

Specification of Letters Patent.

Patented Nov. 5, 1918.

Application filed March 14, 1918. Serial No. 292,411.

To all whom it may concern:

Be it known that I, FRANK M. SALMON, a citizen of the United States, residing at Galesburg, in the county of Knox and State 5 of Illinois, have invented certain new and useful Improvements in Refrigerators, of which the following is a specification.

My invention relates to a refrigerator and its main object is to provide a construction 10 enabling the use of ice as the refrigerant to be dispensed with, and in its stead, a liquid, like water, to be utilized.

In carrying out the main object, a desideratum is to construct a refrigerator in 15 which air is drawn in and forced against splashing water or a water-coated surface in order that the water may cool the air in its passage through the refrigerating chamber or compartment, and in which a means is 20 provided to baffle the air in its passage through the refrigerating chamber in order to obtain the maximum refrigeration therefrom.

Servient objects will appear as the description progresses hereinafter with relation to accompanying drawings, illustrating one preferred embodiment, and in which:—

Figure 1 is a view partly in front elevation and partly broken away and in section 30 to disclose interior details, and

Fig. 2 is a cross sectional view on the line 2—2 of Fig. 1.

For the purposes of my invention, the refrigerator cabinet may be of any desired 35 construction. However it consists of a cabinet supported as from a floor by means of legs or pedestals 3. The cabinet is for example, rectangular in cross section as shown in Fig. 2 transversely, and also rectangular 40 in cross section vertically. To the side and rear walls, shelves 4 are secured in any desired number, having one end in close relation with the adjacent side walls and the other end cut away as at 5 to provide an 45 opening. Attention is called to the fact that these openings 5 are arranged in alternate relation as shown in Fig. 1. An air outlet or vent is provided at 6 at the top of the cabinet. Any suitable means may be provided 50 whereby access may be gained to the interior of the cabinet and for example I suggest a plurality of vertically mounted doors 7, as the front, and desirably having transparent panels 8 therein.

The bottom wall of the cabinet is designated 9 and a blower device 10 rests thereon

and is secured thereto. This blower has an air intake 11 which preferably extends below the wall 9 and it has an air outlet or discharge pipe at 12 discharging into a tank 60 20 provided in the refrigerator between the wall 9 and the lower shelf 4. A blower or fan 14 is disposed within the blower and is operable to induce air through the tube 11 and expel it through the tube 12 against an 65 agitator 14'. The blower and fan may be of any desired particular construction and be operated in any suitable manner. However, I preferably mount the fan shaft which is designated 15 in a wall 16 of the cabinet, 70 disposed below the doors 7. The fan is preferably electrically operated, receiving its energy through feed wires 17 which may lead from the source of electrical energy for the home, store, or other place where the 75 refrigerator may be used.

Referring to the agitator 14', it may consist of a plurality of suitable shaped blades 17' extending from a hub 18 mounted on an axle 19. A water-tight box or receptacle 20 80 is disposed between shelf 4 and wall 9 and rests on the wall 9 and holds a supply of liquid, usually water, as suggested by the liquid representation in the drawing. Bearings 21 receive the ends of the axle or shaft 85 19 and are secured through the side walls of the box 20.

In operation, as the fan 14 turns, air is induced through the pipe 11 and discharged against the agitator 14', forcing the blades 90 thereof successively into the water in the box 20, splashing the water and thus causing the air to contact with the splashed water or the water coated surfaces of the blades. The air therefore is cooled by evaporation of the 95 water before it escapes from the chamber 20. In escaping from the chamber 20, it passes through the opening 5 of the lowermost shelf 4 above taking a zig-zag course since the 100 openings 5 are staggered, and the shelf opposite each opening 5 is closed so that the compartments between the shelves are effectively cooled by the air when the air is forced from the compartments and through 105 the single openings 5 leading therefrom. The air leaves the refrigerator through the opening or vent at 6.

Since I have shown and described merely one preferred embodiment of the invention, 110 it is to be understood that changes in the details of construction may be resorted to with-

out departing from its spirit and scope. For instance, the particular form of fan or blower which is used may be varied as a number of different forms will serve to 5 equally good advantage.

I claim:—

1. A refrigerator including a cabinet divided into superposed food compartments communicating with each other by means of staggered openings, a liquid immersed baffle rotatably mounted beneath the lowermost food compartment, and means for forcing air through said staggered openings, the air impinging the baffle to agitate the liquid, 10 substantially as described.
2. A refrigerator including a cabinet divided into superposed food compartments communicating with each other through staggered openings, a liquid immersed baffle 15 rotatably mounted beneath the lowermost food compartment, a fan for producing an air blast, said air blast operating the baffle to agitate the liquid in the path of movement of the air, substantially as set forth.
- 25 3. A refrigerator having a chamber, a

water container within said chamber, a shaft journaled on said container, an agitator provided with blades, said agitator being rigidly mounted on said shaft, and said blades being passable through the water of 30 the container, a blower within the said chamber, said blower having an intake and an exhaust pipe, a fan within the blower, said fan forcing induced air against the blades of the agitator to successively dip them into the water to turn the agitator and present liquid-coated surfaces to refrigerate the air, shelves disposed above said chamber, each shelf having an outlet opening, said openings being arranged in staggered relation, 35 40 one of said openings communicating with said chamber, and an outlet means above the shelves.

In testimony whereof I affix my signature in presence of two witnesses.

FRANK M. SALMON.
